PRESSURE FLUID MOTOR

Filed Sept. 9, 1932

UNITED STATES PATENT OFFICE

2,040,843

PRESSURE FLUID MOTOR

Elmer G. Gartin, Claremont, N. H., assignor to
 Sullivan Machinery Company, a corporation of
 Massachusetts

Application September 9, 1932, Serial No. 632,414

15 Claims. (Cl. 121—10)

This invention relates to pressure fluid motors and more particularly to improvements in the fluid distribution means and associated hole blowing means for a pressure fluid motor of the 5 type particularly adapted to use in rock drilling tools.

An object of this invention is to provide an improved pressure fluid motor. Another object is to provide an improved pressure fluid motor 10 particularly adapted to use in rock drilling tools. A further object is to provide an improved fluid distribution means for a pressure fluid motor. Yet another object is to provide an improved 15 valve mechanism for a pressure fluid motor. A still further object is to provide an improved fluid distribution means for a pressure fluid motor particularly adapted to use in rock drilling tools and having associated therewith improved hole blowing means. These and other 20 objects will, however, subsequently more fully appear.

In the accompanying drawing there is shown for purposes of illustration one form which the invention may assume in practice.

25 In this drawing,—

Fig. 1 is a central longitudinally extending sectional view of the illustrative embodiment of the improved pressure fluid motor.

Fig. 2 is a view similar to Fig. 1 showing the 30 valve and motor piston in a different position.

Fig. 3 is a view similar to Fig. 1 showing the hole blowing valve and motor piston in hole blowing position.

In this illustrative construction there is shown 35 a motor cylinder 1 herein composed of a plurality of sections united together and having formed therein a cylinder bore 2 containing a reciprocable motor piston 3. As is usual in rock drilling motors, the piston 3 is provided with a 40 forwardly projecting cylindrical extension or striking bar 4 guided within a reduced bore 5 formed in the front motor head 6, and this extension or striking bar is adapted to deliver a series of impact blows to the shank of a usual 45 hollow drill steel suitably mounted within the front motor head. Formed in the extension or striking bar 4 is a series of longitudinal grooves 7 for conducting pressure fluid, when the motor piston is in its rearward position, from the forward end of the cylinder through the front motor head and thence to the bore in the drill steel 50 through which fluid is conducted to the bottom of the drill hole to blow out the cuttings from the hole in a well known manner.

55 The improved fluid distribution means com-

prises an annular valve chamber 8 surrounding the cylinder bore substantially intermediate the ends of the cylinder and formed in the cylinder element 9. Arranged within the valve chamber for reciprocatory movement is an annular flat 5 ring type or disc valve 10 guided at 11 on an element of the improved hole blowing means, as hereinafter described. Fluid is supplied to the valve chamber through a supply connection 12 and passage 13. Formed in the opposite sides of 10 the valve chamber are annular grooves 14 and 15 and the groove 14 is connected through a supply passage 16 to the rear end of the cylinder bore, while the groove 15 is connected to the forward end of the cylinder bore through a supply passage 17. The valve is arranged substantially intermediate the ends of the cylinder, and the supply passages 16 and 17 are of substantially 15 the same length. Communicating with the cylinder bore substantially intermediate the 20 ends thereof is a series of piston controlled exhaust ports 18.

In the operation of the improved fluid distribution means when the parts are in the position shown in Fig. 1, pressure fluid may flow through 25 supply connection 12 and passage 13 to the valve chamber 8. When the valve 10 is in the position shown, the front surface of the valve is seated on concentric annular seats surrounding the groove 15, cutting off communication between the 30 supply passage 13 and the passage 17, and pressure fluid at this time flows through the valve chamber 8 past the rear surface of the valve through groove 14 and passage 16 to the rear end of the cylinder bore, the pressure acting on the 35 rear pressure area of the motor piston to drive the latter forwardly to effect its working stroke. At this time, the forward end of the cylinder bore is connected to exhaust through the exhaust passages 18. As the piston travels forwardly the 40 exhaust passages 18 are covered by the piston head, and upon continued forward movement of the piston a substantial compression pressure is built up by the piston within the forward end of the cylinder bore and in passage 17 and groove 15 at 45 the forward side of the valve. As the rearward edge of the piston head overruns the passages 18, the rear end of the cylinder bore is connected to exhaust through passages 18, and as a result the pressure within the rear end of the cylinder bore 50 and passage 16 and groove 14 at the rear side of the valve is substantially reduced. Consequently the valve 10 is thrown from the position shown in Fig. 1 by the relatively high compression pressure 55 overcoming the piston controlled reduced

pressure acting on the opposed area of the valve, to the position shown in Fig. 2. When the valve 10 is in the position shown in Fig. 2, the rear surface of the valve is seated against the concentric annular surfaces surrounding the annular groove 14, cutting off communication between the valve chamber and passage 16. At this time pressure fluid flows through supply connection 12, passage 13, through the valve chamber, past the forward 5 surface of the valve, through groove 15 and passage 17, to the forward end of the cylinder bore, the pressure acting on the forward pressure area of the motor piston to drive the latter rearwardly to effect its retraction stroke. At this time, the 10 rear end of the cylinder bore is exhausted through exhaust passages 18. As the piston travels rearwardly the exhaust passages 18 are covered by the piston head, and as a result, upon continued rearward movement of the piston a substantial 15 compression pressure is built up by the piston within the rear end of the cylinder bore and passage 16 and groove 14 at the rear side of the valve. As the forward edge of the piston head overruns the exhaust passage 18 the forward end 20 of the cylinder bore is connected to exhaust through exhaust passages 18, and as a result the pressure within the forward end of the cylinder bore and passages 17 and groove 15 at the forward side of the valve is substantially reduced. The 25 valve 10 is then thrown by the compression pressure overcoming the opposed piston controlled reduced pressure, from the position shown in Fig. 2 to the initial position shown in Fig. 1, these operations being repeated during normal operation 30 of the motor. Of course, the areas on which pressures act will be varied to suit conditions to be met.

The improved hole blowing means associated with the fluid distribution means herein comprises a sleeve valve 20 reciprocably mounted in a valve chamber 21 encircling the cylinder bore and formed between the bore in the cylinder element 9 and the sleeve-like portion 22 of the cylinder element 23. The fluid distributing valve 10 is reciprocably mounted on the exterior of the sleeve valve 20. Guided in a bore 24 formed in the cylinder element 9 is a plunger valve 25 having a manually operable push button 26, and this valve is normally held in its released position by 45 a coiled spring 27. When in its inward position this valve closes the throwing passage 16. Formed in the cylinder element 9 is a passage 28 connecting the bore 24 with the fluid supply connection 12, and a passage 29 connecting the bore 24 with 50 the rear end of the valve chamber 21; and formed in the plunger valve 25 is a groove 30 for connecting, when the valve is in its inner position as shown in Fig. 3, the passage 28 with the passage 29. When the plunger valve is released, communication between the passages 28 and 29 is cut 55 off by the cylindrical portion of the valve 25.

In the operation of the improved hole blowing means, when it is desired to effect a hole blowing operation, that is to supply a continuous flow of pressure fluid from the forward end of the motor cylinder through the drill steel to the bottom of the drill hole, the operator presses inwardly on the push button 26, moving the plunger valve 25 to the position shown in Fig. 3. Pressure fluid 60 then flows from the supply connection 12 through passage 28, groove 30 in the valve 25 and passage 29 to the valve chamber 21 to act on the rear pressure area of the sleeve valve 20, moving the latter forwardly from the position shown in Fig. 1 to the position shown in Fig. 3, the sleeve

valve at this time closing the motor cylinder exhaust passages 18. The pressure fluid flowing from the supply connection 12 through passages 13 and 17 causes the motor piston to be retracted, holding the same immovable in its rearmost position, and as a result a continuous supply of pressure fluid is conducted from the forward end of the cylinder bore through the grooves 7 in the piston striking bar and thence through the bore in the drill steel to the bottom of the drill hole. 10 When the plunger valve is released, the valve 20 is automatically returned to the position shown in Fig. 1 by the pressure acting on the forward pressure area of the valve, there being sufficient leakage between the parts to prevent a substantial 15 pressure from being built up in the valve chamber 21 at the rear side of the valve 20.

As a result of this invention, it will be noted that an improved pressure fluid motor is provided having improved fluid distribution means whereby the flow of pressure fluid to the opposite ends of the motor cylinder are substantially equally distributed, the fluid distributing valve being arranged substantially intermediate the ends of the motor cylinder, and by arranging the valve encircling the motor cylinder the lateral dimensions of the motor drill are reduced to a minimum. It will further be noted that associated with the improved fluid distribution means is improved hole blowing means whereby a hole blowing operation 30 is effected in an extremely simple and effective manner. These and other advantages of the improved pressure fluid motor will be clearly apparent to those skilled in the art.

While there is in this application specifically 35 described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a pressure fluid motor, a cylinder having 45 exhaust means, a piston reciprocable in said cylinder for controlling said exhaust means, fluid distribution means for conducting pressure fluid to the opposite ends of the cylinder to effect reciprocation of the piston and including an annular fluid distributing valve encircling the motor cylinder, and a hole blowing device associated with said fluid distribution means and including an exhaust control valve for closing said exhaust means, said exhaust control valve encircling the 50 motor cylinder and said distributing valve guided thereon.

2. In a pressure fluid motor, a cylinder having exhaust means, a piston reciprocable in said cylinder for controlling said exhaust means, fluid 60 distribution means for conducting pressure fluid to the opposite ends of the cylinder to effect reciprocation of the piston and including an annular fluid distributing valve encircling the motor cylinder, and a hole blowing device associated with 65 said fluid distribution means and including a pressure fluid actuated exhaust control valve for closing said exhaust means and a valve operable at will for controlling the supply of pressure fluid to said exhaust control valve, said exhaust control 70 valve encircling the motor cylinder and said distributing valve guided thereon.

3. In a pressure fluid motor, a cylinder having exhaust means, a piston reciprocable in said cylinder for controlling said exhaust means, fluid 75

distribution means for conducting pressure fluid to the opposite ends of the cylinder to effect reciprocation of the piston and including an annular fluid distributing valve encircling the motor

5 cylinder, a hole blowing device associated with
said fluid distribution means and including a pres-
sure fluid actuated exhaust control valve for clos-
ing said exhaust means, said exhaust control
valve encircling the motor cylinder and said dis-
tributing valve guided thereon, and manually op-
erable valve means for supplying pressure fluid to
said exhaust control valve for shifting the latter
from its released position to its operative hole
blowing position.

15 4. In a pressure fluid motor, a cylinder having
a piston controllable exhaust, a piston recipro-
cable in said cylinder, a fluid actuated distribut-
ing valve, passage means for conducting throwing
pressure to said valve, a pressure actuatable ex-
haust controlling valve, and a common valve
member movable to close a throwing passage and
to govern fluid supply to said exhaust control-
ling valve.

5. In a pressure fluid motor, a cylinder having
25 exhaust means, a piston reciprocable in said cyl-
inder for controlling said exhaust means, fluid
distribution means for conducting pressure fluid
to the opposite ends of the cylinder to effect recip-
rocation of the piston including a fluid supply
30 passage and a fluid distributing valve for con-
trolling said passage, and a hole blowing device
associated with said fluid distribution means and
including a fluid actuated exhaust control valve
for closing said exhaust means and a valve oper-
35 able at will for controlling the flow of fluid
through said supply passage to the cylinder inde-
pendently of said distributing valve and for ef-
fecting actuation of said exhaust control valve.

6. In a pressure fluid motor, a cylinder having
40 exhaust means, a piston reciprocable in said cyl-
inder for controlling said exhaust means, fluid
distribution means including supply passages for
conducting pressure fluid to the opposite ends of
the cylinder to effect reciprocation of the piston,
45 and a hole blowing device associated with said
fluid distribution means and including a pressure
fluid actuated exhaust control valve for closing
said exhaust means, said exhaust control valve
encircling the motor cylinder, and a cooperating
50 valve operable at will for cutting off fluid flow
through one of said supply passages and for ef-
fecting actuation of said exhaust control valve.

7. In a pressure fluid motor, a cylinder having a piston controllable exhaust, a piston reciprocable in said cylinder, a fluid actuated distributing valve, passage means controlled by said fluid actuated distributing valve for conducting pressure fluid to the opposite ends of said cylinder, a pressure actuatable exhaust controlling valve, and a common valve member movable to close directly one of said fluid conducting passage means independently of said distributing valve and to govern fluid supply to said exhaust controlling valve.

8. In a pressure fluid motor, a cylinder having
65 exhaust means, a piston reciprocable in said
cylinder for controlling said exhaust means, fluid
distribution means for conducting pressure fluid
to the opposite ends of the cylinder to effect re-
ciprocation of the piston and including an auto-
70 matic fluid distributing valve for controlling the
flow of pressure fluid to the cylinder ends, and a
hole blowing device associated with said fluid
distribution means and including a fluid actuated
75 exhaust control valve for closing said ex-
haust means and a cooperating valve operable

at will for directly cutting off the supply of pressure fluid to one end of said cylinder independently of said distributing valve and for effecting actuation of said exhaust control valve.

9. In a pressure fluid motor, a cylinder having 5
exhaust means, a piston reciprocable in said cyl-
inder for controlling said exhaust means, fluid
distribution means including supply passages for
conducting pressure fluid to the opposite ends of
said cylinder to effect reciprocation of said piston 10
and an automatic fluid distributing valve con-
trolling fluid flow through said supply passages,
and a hole blowing device associated with said
fluid distribution means and including a pressure 15
fluid actuated exhaust control valve for closing
said exhaust means and a cooperating valve oper-
able at will for directly cutting off fluid flow
through one of said supply passages to one end of
said cylinder independently of said distributing 20
valve and for effecting actuation of said exhaust
control valve.

10. In a pressure fluid motor, a cylinder having exhaust means, a piston reciprocable in said cylinder for controlling said exhaust means, fluid distribution means for conducting pressure fluid to the opposite ends of the cylinder to effect reciprocation of the piston and including an automatic fluid distributing valve for controlling fluid flow to the cylinder ends, and a hole blowing device associated with said fluid distribution means and including a pressure fluid actuated exhaust control valve for closing said exhaust means and manually operable valve means for supplying pressure fluid to said exhaust control valve for shifting the latter from its released position to its operative hole blowing position and for interrupting normal operation of said fluid distribution means by cutting off the flow of pressure fluid to one end of said cylinder independently of said distributing valve. 40

11. In a pressure fluid motor, a cylinder having exhaust means, a piston reciprocable in said cylinder for controlling said exhaust means, fluid distribution means for conducting pressure fluid to the opposite ends of the cylinder to effect reciprocation of the piston and including a fluid distributing valve, and a hole blowing device associated with said fluid distribution means including an exhaust control valve for closing said exhaust means, said exhaust control valve providing means for guiding said distributing valve. 50

12. In a pressure fluid motor, a cylinder having exhaust means, a piston reciprocable in said cylinder for controlling said exhaust means, fluid distribution means for conducting pressure fluid to the opposite ends of the cylinder to effect reciprocation of the piston and including a fluid distributing valve, a hole blowing device associated with said fluid distribution means and including a pressure fluid actuated exhaust control valve for closing said exhaust means, said exhaust control valve providing means for guiding said fluid distributing valve, and manually operable valve means for supplying pressure fluid to said exhaust control valve for shifting the latter from its released position to its operative hole blowing position. 55 60 65

13. In a pressure fluid motor, a cylinder having a piston controlled exhaust, a piston reciprocable in said cylinder, a fluid actuated distributing valve, passage means for conducting pressure fluid under control of said fluid actuated distributing valve to the opposite ends of said cylinder, an exhaust controlling valve for closing said cylinder exhaust, and valve means movable to close

directly one of said fluid conducting passage means independently of said distributing valve and for effecting movement of said exhaust control valve into its exhaust closing position.

5 14. In a pressure fluid motor, a cylinder having exhaust means, a piston reciprocable in said cylinder for controlling said exhaust means, fluid distribution means for conducting pressure fluid to the opposite ends of the cylinder to effect reciprocation of the piston and including a fluid supply passage for conducting pressure fluid to the cylinder and an automatic fluid distributing valve for controlling fluid flow through said supply passage, and a hole blowing device associated with said fluid distribution means and including an exhaust control valve for closing said exhaust means and a valve operable at will for controlling the flow of fluid through said supply passage to the cylinder independently of said dis-

tributing valve and for effecting actuation of said exhaust control valve into its exhaust closing position.

15. In a pressure fluid motor, a cylinder having a piston controlled exhaust, a piston reciprocable in said cylinder, fluid distribution means for supplying pressure fluid to the cylinder to effect reciprocation of the piston including a fluid actuated fluid distributing valve for controlling fluid flow to the cylinder ends, passage means for conducting throwing pressure to said valve, an exhaust controlling valve for closing said cylinder exhaust, and common control means operable to effect closure of a throwing passage to interrupt valve movement and to effect movement of said exhaust controlling valve into its exhaust closing position. 5 10 15
